HARLAN P. COLBY, OF GRAND RAPIDS, MICHIGAN.

DESIGN FOR A HOSE-WAGON BODY.

SPECIFICATION forming part of Design No. 19,381, dated October 29, 1889.

Application filed September 9, 1889. Serial No. 323,456. Term of patent 7 years.

To all whom it may concern:

Be it known that I, HARLAN P. COLBY, a citizen of the United States, residing at Grand Rapids, in the county of Kent and State of Michigan, have invented a new and original Design for a Hose-Wagon Body, of which the following is a specification.

My invention has relation to designs for a hose-wagon body; and it consists in the novel 10 design of the whole structure, the leading feature of which consists in the configuration of the box, steps, hand-rails, and dash-board.

The accompanying photographic print, forming part of this specification, is a perspective view looking from the front corner.

A represents the box, having ornamental scroll-work at each end and extending forward underneath the seat, and an ornamental center piece arranged near the middle of the 20 side board; B, the seat, arranged at the front end of the box, the side supporting-pieces resting upon the front end, and are cut away, leaving said floor flush with the top of the side-board.

C is the dash-board, projecting forward 25 from the end of said box at an angle of about forty-five degrees, and is provided with foot-rails c.

D are hand-rails arranged above the side-boards.

E are steps arranged between the front and hind wheels.

F is a foot-board arranged across the rear of the wagon, and is provided with a hand-rail G, substantially in the form of a shepherd's crook.

H is a hand-rail extending across the rear end of the box.

What I claim is—

The design for a hose-wagon body herein 40 described, and shown by the accompanying photographic print.

In testimony whereof I affix my signature in presence of two witnesses.
